CONTROL SYSTEM FOR STRIP MILLS
AND THE LIKEGilbert Edward Adams and Edward Crutchfield
Marshall, Ind.

Application October 9, 1934, Serial No. 747,494

23 Claims. (Cl. 242—75)

Broadly considered, our invention contemplates the provision of an electrical control system, particularly for a plurality of electric motors arranged to work in conjunction with each other, which is automatically operative to bring about controlled deceleration of the motors during that period in their operation at which deceleration is required, as determined by the number of revolutions yet to be made, in order to effect their final stoppage at a predetermined point, and to effect such stoppage at that point. The system is therefore applicable to various industrial installations but is particularly adapted for controlling the operation of tension rolling strip mills intended for progressively reducing the thickness of a strip of metal, and we shall therefore herein refer more specifically to its use for that purpose.

Such strip mills consist essentially of a stand of reducing rolls, a pair of reels located on opposite sides of the stand, and separate driving means, ordinarily electric motors, for the rolls and for each reel together with the necessary circuits, switches and other devices for controlling the action of the motors and the parts driven thereby, the current for the motors being supplied from any suitable source such, for example, as a motor-generator set. In the operation of a mill of this character, a usual practice is to first clamp to one reel one end of the strip to be rolled and to then wind the strip upon it; the other end of the strip is then led through the reducing rolls and clamped to the opposite and now empty reel, following which both reels and the rolls are set in motion so the strip will be unwound from the first reel and, after its passage through the rolls, wound upon the other until substantially the entire length of the strip has been acted upon. Thereupon, the mill is stopped and the direction of rotation of the parts reversed so as to pass the strip through the rolls in the opposite direction, these periodic reversals of the direction of travel of the strip being kept up until the desired reduction of the strip has been effected, the size of the pass between the rolls being of course suitably diminished after each passage of the strip therethrough and the strip being customarily maintained in tension between the unwinding reel and the rolls and between the latter and the winding reel, to which end the reel driving motors are generally so arranged and connected that each can be made to drive its respective reel or the latter can be made to drive the motor and thus be prevented from too rapid rotation by the regenerative braking effect of the motor acting as

a generator to exert the requisite tension on the strip.

Under practical operating conditions, effective control of a mill of this character has been a difficult matter because of various factors necessarily entering thereinto, among which may be mentioned the following: It is of course desirable to move the strip through the rolls as rapidly and uniformly as possible commensurate with a proper rolling thereof so as to complete the desired reduction of the strip in the shortest practicable time with corresponding enhancement of the productive capacity of the mill, but as it is usually impossible to accurately determine the number of turns of strip upon the reels, especially when the latter are in motion and particularly at relatively high speeds, it is necessary for the operator to slow down and/or stop the mill intermittently each time the end of the strip is approached so as to avoid pulling the strip entirely off the reel from which it is being unwound as can, of course, readily occur if the mill is in motion when the last turn is reached. This intermittent starting and stopping or slowing of the mill results in a distinct loss of time and frequently in decrease of uniformity in the product while, moreover, it is not always effective to enable the operator to determine the maximum amount of the strip which may be unwound without danger of pulling it from the reel. Furthermore, the normal speed of travel of the strip through the mill varies widely in accordance with the extent of reduction which has been effected, it being customary to move the strip relatively slowly during the initial pass or passes and to increase the speed progressively for each succeeding pass so that in the last pass the normal speed of travel may be as high as 1200 feet a minute while during the initial one it may be hardly more than a creeping speed, but at these higher speeds the control of the mill becomes increasingly difficult due to the greater momentum of the parts, the thinner gage of the strip and the greater number of turns on the reels as the strip progressively elongates with each pass.

The control system of our invention when applied to a strip mill of the general character to which we have referred greatly minimizes or entirely removes these and other difficulties of operation since it is automatically effective to produce a controlled deceleration of the roll and both reel motors after all but a predetermined number of turns of the strip have been drawn from the reel from which the strip is being unwound and, finally, to bring both said motors to

rest when but one turn or thereabouts remains on the said reel, irrespective of the speed at which the strip is traveling through the mill or the number of turns of the strip on either or both reels. In consequence, the operator of the mill is relieved from the necessity of endeavoring to determine the proper time and point at which to begin deceleration of the mill and finally to bring it to rest while, on the other hand, he can 5 keep the mill operating at a maximum and uniform speed throughout the entire movement of the strip therethrough until the point at which deceleration should commence is reached with the confident assurance that controlled deceleration will then be automatically initiated and the mill finally stopped before the end of the strip can be pulled from the reel it is leaving.

It is therefore an object of our invention to provide a system for controlling in a strip mill 20 or like industrial installation a plurality of motors arranged for conjoint operation in such manner that deceleration thereof will be automatically initiated at the proper time, as determined by the rolling speed to bring the motors 25 to rest at the point at which stoppage is desired.

A further object of the invention is the provision, in conjunction with a strip rolling or generally similar mill comprising a pair of motor driven reels and a stand of motor driven rolls, 30 of a control system which may be operated to automatically initiate a controlled deceleration of both reels and the main rolls when a predetermined number of turns remaining on the unwinding reel has been reached in the process of 35 passing the strip being rolled from one reel to the other and through the rolls located therebetween, and to bring the rolls, reels and their respective motors to rest and terminate the period of deceleration after all, or all but one or fraction of one, or other desired number of turns have been unwound from the said reel.

A further object of the invention is to provide a novel form of fluid governor effective when utilized in a control system such as that of our 45 invention to regulate the rate of deceleration after it has been initiated.

Other objects, advantages and novel features of design, construction and arrangement of parts comprehended by the invention are hereinafter 50 more particularly pointed out or will be apparent to those skilled in the art from the following description of one embodiment thereof in operative association and combination with a strip mill of well known character as illustrated, in 55 large part diagrammatically, in the accompanying drawings in which:

Fig. 1 is a top plan view of a typical tension mill showing its actuating motors but omitting the several parts and connections relating to 60 their control;

Fig. 2 is a vertical section thereof on the line 2—2 in Fig. 1;

Fig. 3 is a simplified wiring diagram showing the circuits employed in accordance with our invention for operating the control mechanism to effect automatic deceleration and stoppage of the mill driving motors;

Fig. 4 is a fragmentary top plan view partly in section in the line 4—4 in Fig. 5 showing certain 70 of the mechanical elements utilized in said control circuits, including the centrifugal fluid governor switch of our invention to which reference has been made;

Fig. 5 is a vertical section thereof on the line 75 5—5 in Fig. 4;

Fig. 6 is an enlarged fragmentary vertical section on the line 6—6 in Fig. 4 of the centrifugal fluid governor control switch and associated parts.

Fig. 7 is a simplified wiring diagram of typical 5 energizing circuits which may be employed in a mill of the character shown in Figs. 1 and 2, with which the circuits shown in Fig. 3 may be interconnected for effecting controlled deceleration of the mill, and 10

Fig. 8 is a graphic representation of a part of the cycle of operation of the mill just prior to and during the deceleration period.

In the several figures, like characters are used 15 to designate the same parts.

The typical tension mill shown in Fig. 1 comprises a four-high roll stand 1 in which are rotatably disposed working rolls 2 provided with backing-up rolls 3, the working rolls being driven through a reduction gear 4 from a direct current 20 motor A. On opposite sides of the roll stand are disposed idler rolls 6L, 6R rotatably supported on suitable stands 7L, 7R to maintain a strip S substantially horizontal during its passage between the rolls 2, while at the opposite ends of 25 the mill, outwardly spaced from the idler rolls, are disposed strip reels 10L, 10R respectively supported for rotation in stands 11L, 11R and provided with means (not shown) for clamping an end of the strip S to their outer cylindrical surfaces. A drive shaft 12L for the left hand reel 10L is interconnected through gears 13L with the shaft 14L of a direct current driving motor LRM and the transmitting motor ST1L of a selsyn set, the purposes of which will hereafter appear, is 30 driven through a flexible coupling 15L from the other end of this shaft. Similarly, the drive shaft 12R of the right hand reel 10R is interconnected through reducing gears 13R with shaft 14R of a direct current driving motor RRM to 40 which in turn is connected, through a flexible coupling 15R, the transmitting motor ST1R of another selsyn set.

In the normal operation of a mill of this character at the initiation of a rolling operation, 45 one end of the strip S is clamped to the reel 10L and the motor LRM is actuated to drive this reel in a clockwise direction as viewed in Fig. 2, to wind the entire strip S thereon. The other end of the strip is then led over the idler 6L, between 50 the working rolls 2, thence over the other idler 6R and secured to reel 10R as indicated in Fig. 2. The strip being now in position for actual rolling, the rolls 2 are adjusted in the usual way, 55 their driving motor A is energized to roll the strip in the direction of the arrow in Fig. 2, and the motor RRM energized to drive the reel 10R in a counterclockwise direction and thus wind the strip thereon after its passage between the rolls 2. Meanwhile, the circuit connected with 60 motor LRM, geared to reel 10L from which the strip is now being unwound, is suitably controlled to provide a regenerative braking effect in the usual way to exert a desired tension on the strip and prevent too rapid rotation of reel 10L in a 65 counterclockwise direction as the strip is drawn therefrom. As reel motors LRM and RRM rotate during this operation, the selsyn transmitters ST1L and ST1R respectively rotate in unison therewith and their effect will hereinafter be 70 more fully explained.

After substantially the entire strip has passed between the rolls 2 and been wound onto reel 10R, the operation of the mill is arrested, preferably just before its end is drawn from the un- 75

winding reel 10L, and the mill is then reversed and the strip passed in the opposite direction, being rewound on reel 10L and unwound from reel 10R, the rolling being thus continued the 5 requisite number of times to effect the desired reduction of the strip.

For the purpose of describing the preferred manner in which the various elements of our improved control system are interconnected to 10 effect deceleration of the driving motors at the proper point in their operation, as determined by the number of turns of the strip remaining on the unwinding reel, we have shown in Fig. 3 a very much simplified electrical diagram including certain mechanical elements so arranged as to permit their electrical connections to be readily followed, which elements are shown in conventional form and in arbitrary mechanical relationships and arrangements which are, 15 of course, in practice subject to modification; in Figs. 4-6 we have shown a convenient mechanical arrangement of certain of these elements, among which electrical connections are preferably extended as indicated in Fig. 3 and in Fig. 7 the 20 mill motor energizing circuits to which the said control system is interconnected by leads, designated by the same symbols and included in the control circuits of Fig. 3.

Referring first to Fig. 7, a motor DM, conveniently a constant speed alternating current motor, drives a generator G for supplying current to motors A, LRM and RRM through the leads a, b, across which the several motors are connected, the passage of this current being controlled by an electrically actuated contactor C in a manner which will hereinafter appear. The fields of motors A, LRM and RRM are excited from any suitable source (not shown) by connection to power leads 115, 118, and those of 25 motors LRM and RRM may be controlled through suitable rheostats in accordance with usual practice to maintain the desired tension on the strip and for other purposes. The same current source is desirably employed for exciting the field 30 G_f of generator G, and a reversing switch E is interposed in the generator field circuit to permit the operator to reverse the mill in the ordinary way.

The voltage output of the generator, and hence 35 the speed at which the mill motors operate, is controlled in accordance with customary practice by suitable variation of the generator field excitation, for which purpose there may be provided a variable rheostat H, operated by a reversible motor FM preferably of the series wound split-field type, and in the lead to one of these fields a switch J is disposed to permit manual control of the current flow therethrough to drive the motor in the proper direction to increase the 40 generator field excitation to accelerate the mill, while in the lead to the other field is a similar switch K to drive the motor in the opposite direction to decrease the generator field excitation and hence decelerate the mill, the switches 45 J and K being normally open except when positively actuated to close the circuits they respectively control. However, the operation of the field rheostat motor FM is subject to modification through the interconnection of our control system in its circuit as will be hereinafter more fully explained.

Referring now more particularly to Fig. 3 the selsyn transmitter ST1L driven by left reel motor LRM as shown, is interconnected with a 50 selsyn receiver SR1L in such way as to drive the

latter at the same speed as the former, motive power being derived from the leads 100, 101, 102 interconnected through a main switch 20 to a suitable source of electric power, for illustration, 440-volt 3-phase A. C. power supply L1, L2, L3, 5 the rotors of these motors being interconnected through the leads 103, 104, 105 to effect synchronous rotation of the rotor of the receiver SR1L in correspondence with the rotation of that of transmitter ST1L as the strip is wound on left 10 hand reel 10L. The selsyn receiver SR1L drives a shaft 25L to which is coupled a shunt-wound resetting motor RSL the purposes of which will hereinafter appear, and a selsyn transmitter ST2L. The latter derives its power from a transformer 15 26 through leads 106, 107, the primary coil of the transformer being supplied with 440 volt current from leads L2, L3, and is interconnected in synchronous driving relation with a selsyn receiver SR2L through power leads 106, 107 and 20 rotor leads 108, 109, 110. The receiver SR2L is positioned at the right hand control desk RD and drives, through a flexible coupling 30R, a revolution counter 31R for giving a visual indication of the number of turns made by left reel 25 motor LRM in winding the strip on left reel 10L.

The shaft 25L also drives the mechanism for actuating the switches which effect automatic deceleration and stoppage of the mill motors when the end of the strip is reached. Said 30 switches, as shown, include a mercury switch M1L actuated by a cam 35L mounted on a shaft 36L and driven through reducing gears 37L from shaft 25L, a similar switch M2L actuated by a cam 38L mounted on a shaft 39L and driven through reducing gears 40L from shaft 36L, and a third such switch M3L actuated by a cam 41L mounted on a shaft 42L and driven through reducing gears 43L from shaft 39L, a cam 44L, also mounted on shaft 42L, controlling a fourth such 35 switch M4L. These switches may of course be of any desired type, suitable for cam actuation, and their specific character forms no part of the present invention; the switches M1L, M2L and M3L, connected in parallel with each other, are 40 connected, however, in circuit with a suitable current source and manual control switch therefor (not shown) and with the solenoid of contactor C so that when one or more of the switches 45 are closed the solenoid may be energized from said current source and contactor C thus held closed to permit operation of the mill, but when all are open this solenoid is deenergized and the mill motor driving circuit thereby interrupted to stop the mill. The functions of switch M4L will 50 hereinafter more fully appear.

The centrifugal control switch GSL to which reference has been made, is likewise actuated by shaft 25L through bevel gears 45L and through an additional cam on shaft 39L as will herein- 60 after more fully appear. This switch is identical with the corresponding switch GSR interconnected with the circuits for controlling the motors when the strip is being unwound from right hand reel 10R and, as shown in Figs. 4-6, is mounted 65 in a frame 50 providing suitable bearings for its driving shaft 25L or 25R of the left and right hand controls respectively. Each of the switches GSL, GSR comprises a substantially conical cup 51 insulated from but secured to a collar 52 70 carried by its supporting shaft 53 which effects its rotation through connection with gears 45. The interior of the cup forms a substantially frusto-conical recess communicating with a short cylindrical bore at its bottom, and contains a 75

suitable quantity of an electrical conductive fluid F such as mercury. Electrical contact with the cup is made by means of a brush 54 engaging a collector ring 55 integral with the cup adjacent 5 its midpoint, while the upper end of the cup is internally threaded for the reception of the externally threaded upper portion of a core 56. The latter comprises a generally conical body 57 having a central bore 58 communicating at 10 its lower end through radial bores 59 with the outer cup chamber and with longitudinal groove 60, rectangular in cross section, which form, with the inner wall of the cup, a plurality of channels in which the fluid F can rise under 15 the influence of the centrifugal force set up by rotation of the cup and the core. The upper end of the core is afforded lateral support through antifriction bearings 61 carried in the upper portion of the switch frame, and a cover 20 plate 62 protects the bearings and forms with adjacent portions of the frame a chamber to retain a lubricant supply for the bearings 61. An insulating tube 63 extends from above this plate through its central bore and into the bore 25 58 of the core, and is secured in the core at its lower end by a pin 64. A plunger 65 extends axially within the tube 63 and is supported by links 66 from a walking beam 67 pivoted on a standard 68 secured to a cross beam 69 of the 30 main frame 50. A spring 70 is connected between the walking beam 67 and the cross beam 69 and urges the former to maintain the plunger in raised position through its connection adjacent the opposite end of the walking beam pivot 35 from that of the plunger connection, this end of the walking beam being actuated through suitable linkage by a roller 71 which rides on a cam 72 carried by shaft 39L. Thus, when cam 72 is rotated by its actuating shaft, plunger 65 is 40 raised and lowered in correspondence with the contour of the cam, and the lower end of the plunger accordingly makes contact with the mercury in the lower end of tube 63 or breaks such contact as the relation of its lower end to the 45 level of the mercury in the tube is varied. As noted, however, the channels formed by grooves 60 communicate with the bore of tube 63 and, since they extend angularly upwardly and outwardly, rotation of the cup sets up a centrifugal 50 force which constrains the level of the mercury to rise in these channels and correspondingly to fall in tube 63, the extent of such raising and lowering being controlled by the speed of rotation of the cup, so that the making and breaking 55 of contact between plunger 65 and the mercury in the tube is thus controlled on the one hand by operation of cam 72 and on the other by the speed of rotation of the cup.

60 The cup 51 of switch GSL and, hence, the mercury disposed therein, are in electrical connection through brush 54 with a lead 111, while the plunger is in circuit with lead 113. The latter is connected to one pole of mercury switch M4L 65 and the former to the other pole of said switch so that when switch M4L is closed, the governor switch GSL is shunted out and its operation therefor has no electrical effect in this circuit, but when switch M4L is open, the governor switch 70 closes the circuit by contact of the plunger with the mercury, and opens it when such contact is broken.

75 The leads 111, 113, when left hand switch GSL is in operation, control the flow of current through the solenoid of a double pole double

throw switch SD which is connected in the generator field rheostat control circuit in such way that when its contacts SD1 are closed through energization of the switch solenoid, the fields of the generator field rheostat motor are placed in 5 circuit with switches J, K, actuated from the operator's desks LD, RD to permit the operator to control the starting and acceleration of the mill and/or reel motors when rolling of a strip is being initiated as well as to control their speed 10 during the major part of its passage between the reels during rolling. When the solenoid of switch SD is deenergized, however, the contacts SD1 are opened, breaking circuits 115, 116 and 117, 118 to interrupt the manual control of the 15 generator field rheostat motor and contacts SD2 are closed, completing circuits 115-119 and 118-120 to energize this motor so as to cause it to reduce the generator field excitation and decelerate the mill. 20

While reference has herein been made to switches and other parts associated with left hand reel 10L and therefore designated by the suffix "L" appended to their distinguishing characters, it will be understood that like controlling 25 mechanisms are associated with the right hand reel for a purpose which will hereinafter appear, and are so designated by the suffix "R".

Thus, right reel motor RRM drives a selsyn transmitter ST1R corresponding to transmitter 30 ST1L, and receiver SR1R is connected with this transmitter through power leads 124, 125, 126 and the rotor connections 127, 128, 129 so as to drive shaft 25R in correspondence with rotation of motor RRM. A resetting motor RSR and a 35 selsyn transmitter ST2R are coupled to shaft 25R, and transmitter ST2R is supplied with energizing current from transformer 26 through connection with leads 106, 107, its rotor being interconnected through leads 130, 131, 132 with 40 that of a selsyn receiver SR2R on left control desk LD, receiver SR2R driving a revolution counter 31L through a flexible coupling 30L. Switches M1R, M2R, M3R, M4R and GSR, corresponding to like switches in the left hand control, are actuated by corresponding cams, cam shafts and reducing gears driven from shaft 25R. 45 These switches are shunted out by suitable connections in the pass selector switch PS on the left control desk when their operation is not required, the same switch shunting out the corresponding ones in the left control when they similarly are not required.

Thus, when the strip is being rolled from left to right, pass selector switch PS interconnects 55 leads 113, 140, shunting out switches GSR and M4R, and leads 136, 137 shunting out switches M1R, M2R, M3R, while for the reverse direction the connections are opened and leads 113, 111 and 135, 136 respectively interconnected, shunting 60 out the corresponding switches GSL, M4L, and M1L, M2L, M3L.

Reference has been made to the resetting motors RSL, RSR which are provided for the purpose of rotating shafts 25L, 25R respectively to 65 reset the control mechanism to proper starting position, i. e., when the counters 31R and 31L register 00000, whenever required, such resetting being usually necessary after the one strip has been rolled and before starting to roll another 70 and also following the breakage of a single strip while it is being rolled or the occurrence of some other abnormal condition. The operation of the resetting motors RSL, RSR is controlled by switches (not shown) located in any convenient 75

position, as for example, on the operating desks LD, RD, preferably so designed as to enable the motors to be operated at high, medium and extremely slow speeds to thereby permit the resetting of the mechanism to be accomplished rapidly and accurately. In addition to their function of controlling the resetting motors, the switches are also preferably arranged to interrupt the power circuits to the selsyn systems ST1, SR1 so that no motion will be communicated by the said systems to the reel motors during the resetting operation. Desirably, these switches are designed for manual actuation, and as they may be of any type and construction suitable for the performance of their intended functions, detailed description or illustration thereof in the drawings is unnecessary.

Operation

20 Preparatory to rolling a strip S, the controls associated with one of the reels, for example, reel 10L, are so adjusted, preferably by resetting motor RSL, that counter 31R reads zero, at which position, provided their operating cams have been 25 properly set, switches M1L, M2L, M3L and M4L are open. By shunting out these switches through pass selector switch PS the circuit controlling contactor C may be closed to start the mill to thereby initially wind the strip on reel 10L. 30 When all or substantially all the strip is wound thereon the mill is stopped, as by opening the circuit controlling contactor C by the manual switch in its power supply line and the free end of the strip then led through the rolls and secured 35 to reel 10R. Counter 31R now shows exactly the number of turns on reel 10L, and as the end of the strip only is on reel 10R, the controls associated with this reel are now operated to set counter 31L to read zero, resetting motor RSR being conveniently utilized for this purpose. 40 Switches M1R, M2R, M3R and M4R are now open and one or more of switches M1L, M2L, M3L are closed in accordance with the positions of their several cams. A circuit is thus established between leads 135, 136, and pass selector switch PS is next thrown to shunt out switches M1R, M2R, M3R and interconnect leads 136, 137, thus closing the circuit between leads 135, 137 and permitting the solenoid of contactor C in 45 the generator output circuit to be energized through its manual switch to start the mill motors and initiate the rolling operation. By means of switch J the operator may then control the operation of motor FM so as to speed up the mill 50 motors as desired to bring the mill to proper rolling speed in the usual way. The strip is thus progressively unwound from reel 10L, rolled, and wound upon reel 10R, one or more of switches M1L, M2L, M3L being kept closed throughout 55 this period by the coordinated operation of their respective controlling cams which are actuated, as above noted, in synchronism with rotation of left reel 10L.

60 As the point at which deceleration is to commence approaches, that is, when all but the last few turns of the strip have been unwound from reel 10L, the cam operating switch M4L opens it, so that it no longer shunts out governor switch GSL. When the cup of the latter is rotating at a 65 relatively high rate of speed corresponding to that of unwinding reel 10L, the level of the mercury in tube 63 of this switch may be insufficient to effect contact with the plunger. The circuit through the solenoid of switch SD is therefore 70 broken by the opening of switch M4L and the

75 solenoid deenergized, thus causing contacts SD1 to open, disconnecting the switches J and K, and contacts SD2 to close, thereby energizing the field rheostat motor through interconnection of leads 119, 120 with leads 115, 118 respectively to cause a 80 diminution in the generator voltage and reduce the mill motor speeds. Such reduction of the speed of the mill motors reduces the rate of rotation of unwinding reel 10L and that of the cup 85 of governor switch GSL, and thus results in a fall of the level of the mercury in the outer channels of the cup and a corresponding rise in its level in its central tube. When the mercury rises therein sufficiently to contact the end of the plunger, the circuit between leads 111 and 113 is again completed, reenergizing the solenoid of switch SD to disconnect leads 115, 118 from 119, 120 respectively and deenergize the field rheostat motor to prevent further diminution in the generator voltage. The mill now continues to operate at its reduced speed but during such operation cam 72 controlling the plunger in switch GSL is being rotated by its actuating mechanism hereinbefore described, gradually raising the plunger in the tube. The mercury having substantially ceased to rise therein, however, upon cessation of the voltage decrease and consequent interruption of the mill deceleration, the rising of the plunger under the influence of the cam breaks its contact with the mercury and again deenergizes the solenoid of switch SD, causing a further diminution in the generator voltage until the mercury again rises sufficiently, as a result of further diminished mill speed, to contact the plunger and again interrupt the deceleration.

35 Of course, if upon opening of switch M4L by its cam the governor cup is rotating so slowly, due to a lesser rolling speed, that the plunger and mercury are in contact, the solenoid circuit is not immediately broken and the mill continues 40 to operate at the same speed until a further amount of strip is withdrawn, corresponding to the plunger travel necessary to open the circuit by operation of the plunger cam but as soon as it does open, deceleration is initiated as above 45 described and thereafter proceeds in like manner.

In practice, these coordinated operations irrespective of what the strip speed may be when they are initiated produce a gradual decrease in the generator voltage and hence in the strip speed throughout the deceleration period and until the 50 end of the strip is very nearly reached, when the strip speed is relatively slow. As approximately the last turn of the strip on reel 10L is reached, the cams operating switches M3L and M2L, having already opened these switches, that operating switch M1L brings it into open position, to open the circuit between leads 135, 137 to deenergize the contactor C thus opening the main driving circuit to bring the mill motors to rest.

55 The strip having thus once been rolled in a single pass through rolls 2 from reel 10L and now being wound upon reel 10R, the mill is operated in the opposite direction by suitable manipulation of reversing switch E, reel motor field rheostats and other mechanisms provided for the 60 purpose. Thus, left reel motor LRM is positively driven in the opposite direction and mill motor A is reversed to draw the strip from the right reel and, after rolling, to rewind it upon the left one, right reel motor RRM meanwhile being so 65 controlled for example by its field rheostat as to exercise the desired regenerative braking effect on right reel 10R. During this reversal the circuit between leads 135 and 137 is maintained by 70 right hand switches M1R, M2R, M3R since the 75

corresponding left hand control switches are shunted out by interconnection of the leads 135, 136 in pass selector switch PS. As the rolling proceeds, right hand governor switch GSR becomes effective, on the opening of right hand limit switch M4R toward the end of the pass, to effect deceleration of motors A and LRM through control of the circuit through the solenoid of switch SD in the manner heretofore carried out by switch GSL, the latter being shunted out through the pass selector switch during the reverse operation of the mill. As the end of the strip on the now unwinding reel 10R is reached, the rate of rolling having been reduced to a minimum, limit switches 15 M3R, M2R, having already been opened by their operating cams switch M1R is similarly opened and interrupts the circuit 135, 137 to open contactor C and deenergize all the mill motors, placing the entire system in condition for the next 20 ensuing pass in the first direction upon proper manipulation of the pass selector switch PS.

The rolling of the strip is thus continued alternately in opposite directions until the desired reduction has been effected, the left hand control mechanism, parts of which are designated with the suffix "L", being brought into play to decelerate and stop the mill when the last part of the strip is being unwound from the left hand reel 10L and wound upon the right hand reel 10R, 25 and the right hand control, corresponding parts of which are designated with the suffix "R", being employed to perform corresponding functions at the end of the passage of the strip in the opposite direction.

30 The rolls 2 are from time to time adjusted, of course, to a somewhat smaller pass and are driven by the motor A in opposite directions corresponding to the direction of the passage of the strip from reel 10L to reel 10R and back again. As 35 each pass produces appreciable elongation of the strip, it is evident that each requires a greater number of turns of the winding reel to take up the entire strip than was required of the winding reel for the preceding pass. Furthermore, the 40 thickness of the strip is reduced as its length is increased, and the practical maximum rolling speed thus correspondingly increases so that while during the first few passes, only a relatively slow movement of the strip from one reel to the other 45 may be permitted, as the end of the operation is approached and during the last few passes, the speed of rolling may be as high as 1200 feet per minute or even higher. However, the automatic control of our invention, as herein described, and 50 irrespective of the rolling speed, effects deceleration of the driving motors at a predetermined rate and automatically in accordance with the number of turns left on the unwinding reel so as to bring the motors to rest at the point where 55 the maximum amount of strip is unwound from the unwinding reel without pulling the end loose therefrom.

The operation of a mill equipped with our control system and the relation between the rolling speed and the time required for complete deceleration therefrom may perhaps be better understood by reference to Fig. 8, in which points along the X-axis represent the amount of strip remaining on the unwinding reel while those on the Y-axis represent the strip speed which, as herein explained, is determined by the voltage output of generator G supplying driving current to the mill.

70 Thus, that portion of the curve v which substantially parallels the X-axis represents the

maximum strip speed V at which the mill is capable of operating, and curves v' and v'' respectively represent in their portion parallel to the same axis other arbitrarily selected speeds V' and V'' at which the mill may operate in practice. In order to bring the mill from maximum speed V to rest at the proper point O, i. e., when no or substantially no more strip can be removed from the unwinding reel without breaking the strip, it is necessary to initiate the deceleration of the mill when some predetermined amount of the strip remains on the unwinding reel, and the portion TO of the curve v represents an assumed ideal deceleration curve for bringing the mill to rest at the point O after it 10 has rolled the major part of the strip at maximum speed. It will now be assumed the mill is in operation under control of the system hereinabove described, and, for clearness of explanation, at a speed V' closely approaching the maximum speed V . When the point T is reached, i. e., when a predetermined number of turns TO remains on the unwinding reel, cam 12 operates to open switch M4 of the right or left control depending on the direction of rolling. As the speed 15 V' is slightly less than the speed V , it is not necessary to immediately initiate deceleration of the mill, however, so the governor GS maintains the circuit in solenoid SD for a short time after M4 opens and the mill continues to operate at 20 the speed V' until an additional amount of strip TU has been removed from the unwinding reel. During this period, the plunger of the governor is being raised by its cam but the speed of the 25 governor corresponding to V' is such that the mercury is not maintained at a level low enough to break the governor circuit. However, as the amount of strip remaining on the reel becomes less than OU, the plunger reaches a position sufficiently elevated to break the governor circuit and 30 switch SD is thereupon actuated to energize field rheostat motor FM to reduce the generator field excitation and in turn the strip speed. This motor is preferably arranged so that when operating at normal speed in the proper direction, 35 it effects deceleration of the mill motors at a rate slightly greater than the "ideal" rate represented by the curve v so that the speed of the mill diminishes along a steeper curve p during further unwinding until it becomes less than the "ideal" 40 or v -curve speed for that point in the strip, i. e., until the mercury in the governor tube rises sufficiently to contact the plunger to reenergize solenoid SD and arrest operation of the generator field rheostat motor. The mill then operates at 45 constant speed q until the strip on the unwinding reel is reduced sufficiently to cause the governor switch to again operate the field rheostat motor as just described. The speed of the mill 50 motors is thus in practice usually decreased by increments during the deceleration period and while in Fig. 8 we have shown it departing rather widely from the "ideal" deceleration curve v for the sake of clearness of illustration, it will be understood that this departure may be greater 55 or less depending on the desired "ideal" deceleration rate, the shape of the governor plunger actuating cam, the rate at which the generator field rheostat motor reduces the mill speed when 60 it is in operation and other factors.

70 It will also be understood that when the mill is being operated at any other rolling speed, such as V'' , materially less than the maximum, it will be maintained at this speed for a considerable period, TW, after switch M4 opens and thus until 75

but OW turns remain on the unwinding reel, since obviously when the mill is operating at a slow speed, deceleration rates being equal, less time is necessary to bring it to rest than when it is operating at high speed. When all but OW turns have been removed, however, deceleration of the mill is initiated as hereinabove described to ultimately bring the mill to rest at point O.

Of course, the various mechanisms may be so arranged that once deceleration is initiated the generator field rheostat motor is kept in constant operation throughout the deceleration period, and the deceleration curve v is exactly adhered to by the strip speed, but we prefer to operate the system to maintain a controlled deceleration in relation to the strip speed as above described.

While we have herein shown and described one embodiment of our invention with considerable particularity, and especially as it may be employed for controlling a typical strip mill of a specific character, it is to be understood that we do not desire or intend that our invention shall thereby in any way be limited or restricted in its employment as a control system for other mills or for mechanisms of different character, nor do we confine ourselves to the said specific embodiment of our invention as the latter may readily be modified to suit varying conditions and to perform various functions other than those herein particularly mentioned; moreover, changes and modifications in the form, construction and arrangement of the several mechanisms employed, the parts thereof and the manner of their interconnection will readily occur to those skilled in the art and may be made if desired without departing from the spirit and scope of the invention as defined in the appended claims.

Having thus described our invention, we claim and desire to protect by Letters Patent of the

United States:

1. The combination with a current source, control means therefor operable to progressively diminish the current delivered therefrom and an electric motor energized by said delivered current, of means actuated by the motor operative to successively energize and deenergize the control means to thereby effect progressive diminution of the motor torque in predetermined timed relation with the movement of the motor and means actuated from the motor actuated means for interrupting said current at a predetermined interval after the control means are first brought into operation.

2. The combination with a current source and an electric motor actuated thereby, of a centrifugally responsive switch driven by the motor and motor current control means adapted to be energized thereby operative to control the motor to effect progressive diminution of its torque in predetermined timed relation with the movement of the motor and another switch having a common drive with the first switch operative to deenergize the motor when said torque reaches a predetermined value.

3. The combination with a current source and an electric motor actuated thereby, of means driven by the motor comprising a centrifugally responsive switch including a rotatable cup, a conductive fluid disposed therein and a plunger operable to contact said fluid, means interconnected with the motor for driving said cup at a speed corresponding to that of the motor, a cam driven from said last mentioned means for moving said plunger, means controlling said current source, and means interconnecting the cup and

the plunger in circuit with said control means to effect progressive deceleration of the motor.

4. In combination with a pair of electric motors, means for driving each of said motors electrically, means interconnecting the motors for mechanically driving each from the other while either is being driven electrically, means respectively actuated by each motor operative while said motor is being mechanically driven to control the voltage supplied to the other motor to effect progressive deceleration thereof in predetermined relation to the rotation of the motor being driven mechanically therefrom.

5. In combination with a pair of electric motors, a source of current supply therefor, means for reducing the current so as to decelerate the motors and means mechanically interconnecting the motors, a control system operative to actuate said current reducing means in predetermined timed relation with the rotation of one of the motors comprising a switch interconnected with the current reducing means and means driven by said motor for actuating said switch.

6. In combination with a pair of electric motors, a source of current supply therefor, means for reducing the current so as to decelerate the motors and means mechanically interconnecting the motors to drive either from the other, a control system adapted to automatically actuate said current reducing means comprising a switch, means for actuating said switch in correspondence with the rotation of the driven motor, and another switch in circuit across the contacts of said first mentioned switch operative to shunt out the first mentioned switch during a predetermined period of operation of the driven motor.

7. In combination with a pair of electric motors, a source of current supply therefor, current control means for reducing and finally shutting off the current so as to decelerate the motors and finally to bring them to rest, and means selectively actuated by either motor to drive the other motor therefrom, a control system comprising switch means operative to actuate the current control means to progressively decelerate the driving motor during a predetermined number of revolutions of the driven motor, and other switch means also interconnected therewith operative to actuate the current control means to shut off the current during the next ensuing revolution of the driven motor.

8. In combination with a pair of electric motors, a source of current supply therefor, current control means for reducing and finally shutting off the current so as to decelerate the motors and finally to bring them to rest, and means selectively actuated by either motor to drive the other motor therefrom, a control system comprising a switch in circuit with the current control means actuated in accordance with the number of revolutions made by the driven motor operative at a predetermined point in the operation thereof to interrupt the switch circuit, centrifugal governing means thereafter operative to successively energize and deenergize the current control means to effect progressive deceleration of the motors through an ensuing predetermined number of revolutions of the driven motor, other switch means for interrupting the flow of current to the motors after said revolutions have been accomplished, and means actuated in accordance with the rotation of the driven motor for actuating all of said switch means.

9. The combination with a pair of winding

75

reels and respective driving motors therefor adapted to alternately unwind a strip from one reel and wind it on the other, of control means for the motors automatically operative to decelerate the then winding reel in predetermined relation to the number of revolutions thereafter to be made by the other reel comprising switch means actuated in accordance with the rotation of said other reel operative to progressively 10 reduce the flow of current through the winding reel motor.

10. The combination with a pair of winding reels and respective driving motors therefor adapted to alternately unwind a strip from one reel and wind it on the other, of control means for the motors automatically operative to decelerate the motor of the then winding reel in predetermined relation to the number of revolutions thereafter to be made by the other motor 15 comprising switch means actuated in accordance with the rotation of said motor operative to reduce the flow of current through the winding reel motor during the subsequent revolutions of the other motor, and other switch means for interrupting said current at the conclusion of said 20 subsequent revolutions.

11. The combination with a pair of reels and respective driving motors therefor operable to alternately unwind a strip from one reel and 30 wind it on the other, of control means for the motors operative in accordance with the number of revolutions made by the unwinding reel to reduce the current flowing through the winding reel motor to effect deceleration thereof during a predetermined number of the revolutions 35 of the unwinding reel, said means comprising a shaft, means for rotating the shaft in correspondence with the rotation of the unwinding reel, switch means actuated by said shaft operative to progressively reduce the current to the winding reel motor upon completion of a predetermined number of revolutions of the shaft prior to attainment of its limit of rotation as determined by said strip, and governing means 40 for thereafter controlling the rate of deceleration of said motor during the period of deceleration.

12. The combination with a pair of reels and respective driving motors therefor operable to alternately unwind a strip from one reel and wind it on the other, of control means for the motors operative in accordance with the number of revolutions made by the unwinding reel to reduce the current flowing through the winding reel 50 motor to effect deceleration thereof during a predetermined number of revolutions of the unwinding reel, said means comprising a shaft, means for rotating the shaft in correspondence with the rotation of the unwinding reel, switch means actuated by said shaft operative to progressively reduce the current to the winding reel motor upon completion of a predetermined number of revolutions of the shaft prior to attainment of its limit of rotation as determined by said strip, 55 governing means for thereafter controlling the rate of deceleration of said motor during the period of deceleration, and other switch means operative to shut off said current entirely substantially upon attainment by the shaft of its said 60 limit.

13. In combination with a pair of reels and a driving motor for each reel whereby a strip may be unwound from one reel and wound on the other reel, a control system operative to automatically reduce the current flowing to the mo- 70

tor of the winding reel after the unwinding reel has made a predetermined number of turns so as to decelerate said motor during an ensuing predetermined number of such turns, and to then shut off the current to said motor, comprising a cam actuated switch, means for actuating said switch in correspondence with the turns of the unwinding reel to reduce said current after a predetermined number of said turns, governing means actuated by said switch actuating means for controlling the rate of deceleration of the winding reel motor resulting from the reduction of its current during a further predetermined number of turns of the unwinding reel, and other switch means also actuated from said actuating means for then shutting off the current to said motor.

14. In combination with a pair of reels, a driving motor for each reel and a source of motor driving current whereby a strip may be unwound from one reel, and wound on the other reel, a control system operative to automatically reduce the current flowing to the motor of the winding reel after the unwinding reel has made a predetermined number of turns so as to decelerate said motors during an ensuing predetermined number of such turns, and to then shut off the current to said motors, comprising electrical means operative to reduce the current flowing to said motors, centrifugally responsive switch means operative to regulate said electrical means to control the rate of deceleration of the motors, a cam actuated switch operative to render the centrifugally responsive means effective only during a predetermined number of turns of the unwinding reel, other switch means for then interrupting said current to bring the motors to rest, and means for actuating each of said switch means in accordance with the rotation of the unwinding reel motor.

15. The combination with a strip mill comprising a pair of reels and a driving motor for each reel whereby a strip wound on one reel may be unwound therefrom and wound on the other reel, of a control system for said motors comprising revolution counters for respectively recording positively and negatively the revolutions of each reel, means for actuating each counter in accordance with the movement in either direction of its respective reel, switch means including a centrifugally responsive fluid governor interconnected with the means actuating the counter recording the negative revolutions of the unwinding reel operative on the attainment of a predetermined number of said revolutions to reduce the current flowing to the winding reel motor and thereafter to regulate the average rate of motor deceleration induced by such reduction during an ensuing predetermined number of negative revolutions of the unwinding reel, and other switch means also actuated from said counter actuating means for then interrupting said current to bring both said motors to rest.

16. In an electrical control system, a plurality of cam actuated switches interconnected in parallel, a cam for actuating each switch, a shaft supporting each cam and reducing gears interposed between each shaft and an adjacent one operative to effect differential rotation of the several shafts in predetermined relation with the operation of the controlled mechanism to thereby simultaneously actuate all of said switches at a predetermined point in said operation.

17. A centrifugally responsive control switch comprising a support, a cup rotatable in said sup- 75

- port, means for rotating the cup, electrically conductive fluid disposed in the cup, a plunger carried by the support having an end extending axially into the cup, and adapted to effect contact with said fluid when the cup is rotating and means for effecting movement of the plunger relatively to the fluid in timed relation with the rotation of the cup.
18. A centrifugally responsive control switch comprising a support, a cup rotatable in said support, means for rotating the cup, electrically conductive fluid disposed in the cup, a plunger carried by the support having an end extending axially into the cup, and adapted to effect contact with said fluid when the cup is rotating at a speed not greater than a predetermined speed, and means actuated from the cup rotating means for moving said plunger axially in the cup to thereby selectively make and break contact thereof with said fluid independently of the speed of rotation of the cup.
19. In an electrical switch, a rotatable cup having an inverted frusto-conical chamber, a frusto-conical core disposed in said chamber having longitudinal grooves forming channels with the walls thereof, an axial bore, and passages interconnecting said bore and said channels, electrically conductive fluid in said bore, channels and passages, a plunger extending longitudinally in said bore operable to make and break contact with said fluid, and means operative to effect vertical movement of the plunger in predetermined timed relation with the rotation of the cup.
20. In combination with an electric motor, means for supplying driving current thereto and means operable to diminish said driving current, means actuated from the motor operable to actuate said current diminishing means intermittently in predetermined timed relation with the operation of the motor to progressively reduce the motor speed, and other means actuated from said

motor actuated means operative to interrupt the driving current when the motor reaches a predetermined reduced speed to thereby bring the motor gradually to rest.

21. In combination with an electric motor, means for supplying driving current thereto and means operable to diminish said driving current, a control system operable to actuate said current diminishing means comprising a control circuit, means for successively opening and closing said circuit in predetermined timed relation with the operation of the motor to thereby progressively diminish the driving current to decelerate the motor, and a second circuit including means for interrupting the driving current, and means for controlling the second circuit to interrupt the driving current in predetermined timed relation with the operation of the first circuit.

22. In a motor control system, a motor driving current control circuit, means actuated from the motor in timed relation with its rotation operable to successively energize and deenergize said circuit in accordance with the motor speed thereby to effect progressive subsidence of the motor driving current and means actuated by said motor actuated means for interrupting said current when it reaches a predetermined diminished value.

23. In a motor control system, a motor driving current control circuit, a switch for opening and closing said circuit, means operable to actuate said switch, means driven from the motor in timed relation with its rotation operable to successively energize and deenergize said switch actuating means in accordance with the speed of the motor to thereby cause progressive subsidence of the motor driving current and another switch actuated by said motor driven means for finally interrupting said current to stop the motor.
